UNITED STATES PATENT OFFICE.

JOHN H. TYLER, OF WINCHESTER, KENTUCKY.

WINDOW-SASH.

992,393.

Specification of Letters Patent. Patented May 16, 1911.

Application filed May 27, 1910. Serial No. 563,767.

To all whom it may concern:

Be it known that I, JOHN H. TYLER, a citizen of the United States, residing at Winchester, in the county of Clark and State of Kentucky, have invented new and useful Improvements in Window-Sashes, of which the following is a specification.

This invention relates to window sashes and one of the principal objects of the same is to provide simple, reliable and efficient means for holding the window pane in the sash without the use of putty.

Another object of the invention is to provide spring fasteners connected to wooden strips for holding the window pane in place, said spring fasteners being disposed in recesses in the sash.

Still another object of the invention is to provide means for securing window panes in sashes without the use of putty, said means being readily disconnected from the sash to permit the removal of the window pane or for securing a window pane in place of a broken glass.

These and other objects may be attained by means of the construction illustrated in the accompanying drawing, in which,—

Figure 1 is a view in elevation of a sash looking at the inside of the same, the means for holding the glass in the sash being made in accordance with my invention. Fig. 2 is a horizontal section of the same, a portion of the central part of the sash and glass being broken away. Fig. 3 is a plan view of one of the spring fasteners.

Referring to the drawing, the numeral 1 designates the sash comprising the horizontal and vertical members, each provided with a stop 2 upon the outer side of the inner portion of said members against which the glass 3 bears. A recess 4 is formed in each of the members of the sash at the inside of the glass 3. The recess 4, as clearly illustrated in Fig. 2 of the drawings, has its side walls slightly beveled toward each other and connected with an enlarged inner wall. Holding strips 5 for securing the glass in place in the sash are each provided with a longitudinal groove 6, and secured at intervals in the groove 6 are the spring fasteners, said fasteners each comprising a wire or flat metal band having a base portion 7, parallel arms 8 and opposite outwardly curved bearing

members 9. These spring fasteners are secured to the strips 5 by means of a cleat or strip 10 which bears against the base members 7 of the spring clasp and is secured in the groove 6 of the strip 5. The strips 5 are of substantially dovetailed shape in cross section so as to provide a space between the beveled side walls thereof and the straight side walls of the groove 6. By this arrangement, it will be noted that the arms 8 as well as the curved bearing members 9 may be forced toward each other to permit their insertion between the reduced entrance of the groove. It will be noted that when the curved bearing members of the spring fasteners are positioned within the enlarged rounded recess of the groove, the said bearing members will swing into tight engagement with the said rounded wall and the shoulders formed at the juncture of the said rounded members and their arms 8 will tightly engage with the shoulders formed at the juncture of the inclined and rounded walls of the groove 4, thus effectively securing the strips 5 and preventing accidental movement of the same in any direction. The strips 5 may be mitered at three of the corners, as shown at 11, while at one of the corners one of said strips passes the other, as shown at 12. One of the bars or members of the sash may be removable to permit the pane and the strip 5 to be slipped into place, after which the member is secured in position.

From the foregoing it will be obvious that by means of my invention window panes may be readily secured in the sash without putty, and that should a window pane be broken another can be readily secured to the sash in its place. Moreover, it will be seen that the cost of producing the sash and securing the pane therein would be less than the cost of securing a pane in place by putty, while by my invention the window pane would be held more securely, and the annoyance of the breaking away of the putty be eliminated.

I claim:—

A window sash provided with grooves upon its inner faces, said grooves comprising inwardly inclined side walls communicating with an enlarged curved rear wall, holding strips each provided with a longitudinally

100

extending recess, spring securing elements adapted to be received within said recesses, strips within the recess adapted to engage the spring fasteners, said strips being of a substantially dovetailed formation, the spring fastening devices each comprising a single member having a base portion, parallel arms and opposite outwardly curved

bearing members, all substantially as and for the purpose set forth. 10

In testimony whereof I affix my signature in presence of two witnesses.

JOHN H. TYLER.
